US00D864982S

(12) **United States Design Patent** (10) **Patent No.:** **US D864,982 S**
Johnson et al. (45) **Date of Patent:** **** Oct. 29, 2019**

(54) **DISPLAY SCREEN OR PORTION THEREOF WITH GRAPHICAL USER INTERFACE**

(71) **Applicant:** **LIFE TECHNOLOGIES CORPORATION**, Carlsbad, CA (US)

(72) **Inventors:** **Brian Johnson**, Rockton, IL (US); **Rachel Wihlborg**, Rockford, IL (US); **Kevin Abrams**, Loves Park, IL (US); **David Lu**, Austin, TX (US); **Todd Lefelt**, Los Angeles, CA (US); **Magdalena Wielopolski**, Los Angeles, CA (US); **Eve Songdej**, Los Angeles, CA (US); **Matthew Murray**, Los Angeles, CA (US); **Aron Wahl**, Los Angeles, CA (US); **Austin Beer**, Los Angeles, CA (US); **Charlie Hart**, Los Angeles, CA (US); **Agnes Won**, Los Angeles, CA (US); **Shane Nehring**, Oakland, CA (US)

(73) **Assignee:** **Life Technologies Corporation**, Carlsbad, CA (US)

(**) **Term:** **15 Years**

(21) **Appl. No.:** **29/611,390**

(22) **Filed:** **Jul. 20, 2017**

(51) **LOC (12) Cl.** **14-04**

(52) **U.S. Cl.**

Assistant Examiner — John M Otte

CLAIM

The ornamental design for a display screen or portion thereof with graphical user interface, as shown and described.

DESCRIPTION

The FIGURE is a front view of a display screen or portion thereof with graphical user interface showing our new design.

The broken line showing of a display screen is included for the purpose of showing portions of the article which form no part of the claim.

1 Claim, 1 Drawing Sheet
